METHOD AND PRODUCT FOR INHIBITING
HYDROUS DISINTEGRATION OF SHALE
BY AQUEOUS DRILLING MUDSNorman E. Martello, Turtle Creek, Pa., assignor

corporation of PennsylvaniaNo Drawing. Application October 9, 1944,
Serial No. 557,932

13 Claims. (Cl. 252—8.5)

1

This invention relates to the treatment of aqueous drilling muds, and particularly to the treatment of those muds which are employed in the control of what is commonly referred to as "heaving shale" encountered in the drilling of oil wells.

My invention relates to the compounding and use of drilling muds in such composition that when employed in drilling through a formation of heaving shale, the disintegration of this shale is substantially retarded. According to my invention, this may be achieved by using substantially water-insoluble alkali metal metaphosphate or mixtures of substantially water-insoluble alkali metal metaphosphates or mixtures of one or more water-insoluble alkali metal metaphosphates with certain water-soluble salts in the drilling mud.

In drilling oil wells, for example, it is customary to employ a mud or fluid which performs various well known functions. The mud is circulated from a pit or sump above the ground through the drill pipe, through and around the drilling bit where it picks up the chips formed by the drill, and then up the bore to screens where the chips and cuttings are removed. Other functions of these muds are to seal gas, oil, and water formations and to lubricate both the drilling tools and the drill pipe.

It has been well known for many years that there exist certain geological formations which are termed "heaving shale formations" or "heaving shale." As stated in U. S. Patent 2,165,824, issued to Vietti and Garrison, the terms denote shale strata which do not remain consolidated during the drilling operations. It is believed that the disintegration of this shale is due to its hydrolysis or hydration and numerous methods have been proposed to inhibit or prevent this disintegration. In many instances the shale falls into the hole when drilling tools are removed or the shale may disintegrate and keep running or caving into the hole and the mud stream during the drilling operation itself. Some of these shales swell when hydrolyzed and may result in pinching of the drill pipe and cause it to twist off, a serious event, the consequences of which are well known to those skilled in the oil well drilling art. Shales which hydrolyze or hydrate, whether they swell, as bentonite, or not are referred to herein as hydrolyzable shales.

2

Several theoretical proposals have been offered for explaining the disintegration of the shale which may be controlled by mechanical methods. One such theory is that the disintegration is due to gases under high pressure which exist in the fissures of the shale strata while another theory is that this type of shale is under considerable stress which is relieved by the drilling of a hole through the strata, the caving of the shale thereby relieving this stress.

It is now a generally accepted fact that the aqueous phase of the drilling mud causes the disintegration of those shales which require chemical treatment for effective control. Numerous methods have been suggested for chemically controlling heaving shale, one such method involving the incorporation in the mud of such water-soluble salts as calcium chloride, magnesium chloride, or sodium nitrate. Another method of chemical control is disclosed in the Vietti and Garrison patent previously referred to. This involves the incorporation of certain sodium silicates in which the molecular ratio of sodium oxide to silica falls within the range of 1:2 up to 1:3.9.

A drilling mud employing sodium silicate to chemically control the disintegration of shale generally comprises clays, water, and from 20% to 70% by volume of a sodium silicate. Frequently other solid materials are added to the mud for increasing the specific gravity, commonly used weighting materials being barytes, iron oxide, or the like.

It is well known that certain water-soluble polyphosphoric acid compounds in very small concentrations are extremely effective in reducing the viscosity of drilling muds, but these materials are not effective in chemically controlling the disintegration of hydrolyzable shale. For example, I have found that a concentration of as much as 25% of sodium phosphate glass of the Graham's salt type, based on the weight of the water used in the drilling mud does not inhibit the disintegration process. Other water-soluble phosphoric acid compounds are equally ineffective.

In my invention, I employ water-insoluble crystalline alkali-metal metaphosphates. These phosphates are generally termed water-insoluble, because they have a limiting solubility in distilled water of only a few parts per million,

whereas sodium phosphate glasses of the Graham's salt type are miscible in water in nearly all proportions. Thus water-insoluble crystalline NaPO_3 , commonly referred to as sodium monometaphosphate or Maddrell salt is soluble in distilled water to the extent of about 5 P. P. M., and water-insoluble KPO_3 , referred to in the literature as potassium monometaphosphate, is soluble in distilled water to the extent of about 40 P. P. M. In contrast with these solubilities, the phosphate glasses have practically unlimited solubilities, and solutions of 50% or greater concentration may readily be made. The phosphates I employ have a limiting solubility in pure water at ordinary temperature of less than 0.005%.

The effectiveness of the water-insoluble crystalline alkali metal metaphosphates in controlling the viscosity of drilling fluid has been disclosed in several recently filed applications. Partridge in application Serial No. 522,974, filed February 18, 1944, which issued as U. S. Patent 2,393,560 on January 22, 1946, and which is a continuation-in-part of Serial No. 465,456 filed November 13, 1942, discloses the addition of very small amounts of water-insoluble crystalline alkali metal metaphosphate in solid form directly to the drilling mud. Martello in application Serial No. 522,955, filed February 18, 1944, which issued as U. S. Patent 2,414,381 on January 14, 1947, discloses the addition of a slurry or suspension of mixtures of water-insoluble crystalline alkali metal metaphosphate to drilling mud preparations. Tjoflat in Serial No. 522,973, also filed February 18, 1944, discloses the addition of water-insoluble crystalline alkali-metal metaphosphate solubilized by any one of a number of metallic salts, both inorganic and organic in nature. It should be pointed out that in each of these applications, the phosphate addition is made for the purpose of reducing and controlling the viscosity of the drilling mud and it is the general practice to employ substantially less than 0.5% of phosphate chemical based on the total weight of the drilling mud.

I have referred to water-insoluble sodium metaphosphate and water-insoluble potassium metaphosphate by which I mean the sodium salt, often designated as Maddrell salt, and the corresponding potassium salt, which were described by R. Maddrell in *Philosophical Magazine*, series 3, vol. 30 (1847), page 329, and have been called salts of monometaphosphoric acid or monometaphosphates by T. Fleitmann in *Poggendorf's Annalen*, vol. 78 (1849), pages 360-363. The water-insoluble crystalline sodium metaphosphate may be made by heating NaH_2PO_4 or $\text{Na}_2\text{H}_2\text{P}_2\text{O}_7$ to a temperature above 300 and below 500° C. and cooling either rapidly or slowly. It is advisable to heat the NaH_2PO_4 or $\text{Na}_2\text{H}_2\text{P}_2\text{O}_7$ to a temperature of from 400 to 450° C. in order to obtain a product which consists almost entirely of the water-insoluble crystalline sodium metaphosphate.

Water-insoluble crystalline potassium metaphosphate may be prepared by heating KH_2PO_4 to any temperature above about 300° C. and up to or above its melting point, which is slightly above 800° C., and cooling either rapidly or slowly. If the material is heated to a melt, it should not, however, be cooled with sufficiently extreme means to produce a readily water-soluble glass. When temperatures in the lower part of the range are employed, heating should be conducted for a sufficient time to insure that the product will consist substantially entirely of the water-

insoluble crystalline potassium metaphosphate. Methods for making the water-insoluble potassium phosphates are described by Pascal, *Bull. Soc. Chim.* 1924 35, 1119.

5 In my invention, I may employ a water-insoluble potassium monometaphosphate which is solubilized in water by a water-soluble, ionizable calcium, sodium, lithium, or ammonium compound. Typical of the solubilizing compounds which may be used are hydroxides, carbonates, bicarbonates, sesquicarbonates, chlorides, sulfates, nitrates, silicates, orthophosphates, pyrophosphates, tripolyphosphates, metaphosphates, borates, acetates, and the salts of natural organic radicals derived 10 from tannin and lignin. In addition, the water-insoluble KPO_3 may be solubilized by the water-insoluble NaPO_3 .

If I use the water-insoluble NaPO_3 it may be solubilized by a water-soluble, ionizable calcium, 15 potassium, lithium, or ammonium compound selected from the group of typical compounds stated above in connection with the monometaphosphate.

The mixture of the water-insoluble phosphate 20 and the solubilizing agent may be added in the form of a slurry to the mud or the necessary amounts may be added in dry form if a dry compound is selected for solubilization. I may also add the water-insoluble KPO_3 or the Maddrell 25 salt in dry form without additional solubilizing agents where the drilling mud itself contains a solubilizing material such as NaCl or KCl . I do not intend to limit myself to any particular methods of compounding or preparing the drilling 30 muds employed by me in effecting the operation of my invention.

While the materials I employ are effective over 35 a wide range of concentration, from about 1% to about 30% based on the weight of the water used in the mud, I have found that concentrations of from about 4% to about 10% or 20% are satisfactorily effective and economical in cost.

Uniform samples of heaving shale are not 40 readily obtainable for laboratory experimental purposes. However, as described by Baker and Garrison in volume 34, No. 6, *Transactions of American Institute of Chemical Engineers*, certain native kaolins react similarly to the hydrolyzable shales encountered in well drilling. I prepared small lumps of Georgia kaolin which were 45 oven-dried at a temperature of 110° C. for twelve hours. These were placed in large test tubes containing varying concentrations of different solutions I examined for preventing the disintegration 50 of the clay lumps.

In each series of tests I used a blank of distilled water and also a sample consisting of two volumes of a commercial sodium silicate having 55 a specific gravity of 50° Baumé and one volume of saturated sodium chloride solution. This latter solution is used by Baker and Garrison as a standard for determining whether or not certain core samples suspected of being hydrolyzable are 60 subject to disintegration. According to these authors, representative portions of core samples are placed in companion test tubes one containing water and the other containing the silicate-sodium chloride solution. Any cracking, swelling, or 65 disintegration of the samples immersed in water is a warning that heaving shale has been tapped. The sample immersed in the silicate-chloride solution should not be subject to this disintegration so that I have included the mixture in each series 70 of the tests I have conducted.

The following examples are illustrative of the various tests which I have made:

Example No. 1

[Treating agents used are equal parts of KPO_3 (insoluble potassium monometaphosphate) and $NaPO_3$ (insoluble sodium monometaphosphate)]

Test No.	Type of aqueous suspension	Appearance of shale after 48 hours
1	Control: Distilled water	About $\frac{1}{6}$ of specimen broke in fine pieces, rest broke up into large pieces.
2	2% KPO_3 - $NaPO_3$	Broke up in some small and some large pieces. Less fine than pieces in Test No. 1.
3	4% KPO_3 - $NaPO_3$	About same as Test No. 2.
4	8% KPO_3 - $NaPO_3$	Do.
5	12% KPO_3 - $NaPO_3$	Specimen uncracked, retained its original shape.
6	16% KPO_3 - $NaPO_3$	Specimen had small crack in edge, retained its original shape.
7	20% KPO_3 - $NaPO_3$	Specimen same as in Test No. 5 except few small pieces flaked off one side.
8	Control: Sodium Silicate	Several pieces cracked off one side, some flaked off other side, rest of specimen retained its original shape.

In the above tests, Example 1, the ratio of KPO_3 : $NaPO_3$ is 1:1.

Example No. 2

[Treating agents used are KPO_3 (insoluble potassium monometaphosphate) and sodium phosphate glass]

Test No.	Type of aqueous solution	Appearance of shale after 72 hours
1	Control: Distilled water	Specimen broke up in about 20 pieces.
2	Control: Sodium Silicate	Specimen cracked clear across but retained its form. Piece cracked off bottom edge.
3	Control: 2 volumes sodium silicate 1 volume saturated NaCl solution	Specimen broke up into about 10 pieces.
4	0.75% KPO_3	Specimen in 1 piece. Few small pieces spalled off sample.
5	0.375% sodium phosphate glass	Specimen broke in about 6 pieces.
6	1.5% KPO_3	Specimen in 1 piece. Few small pieces spalled off.
7	0.75% sodium phosphate glass	Specimen broke into 2 large and 2 small pieces.
8	4.5% KPO_3	Do.
9	2.25% sodium phosphate glass	Specimen broke into 4 pieces.
10	7.5% KPO_3	Two pieces broke off specimen. Crack across top of specimen and some small pieces spalled off.
11	3.75% sodium phosphate glass	Specimen in one piece. Little spalled off.

NOTE: The sodium phosphate glass used in the above tests is a phosphate glass having a molar ratio of 1:1 Na_2O : 1 P_2O_5 .
In the above tests, Example 2, the ratio of KPO_3 to sodium phosphate glass is 2:1.

Example No. 3

[Treating agents used are KPO_3 (insoluble potassium monometaphosphate) and NaCl]

Test No.	Type of aqueous suspension	Appearance of shale after 24 hours
1	Control: Distilled water	Specimen crumbled and broke up with few large pieces on top.
2	Control: 2 volumes Sodium silicate 1 volume Saturated NaCl solution	About $\frac{1}{2}$ of specimen crumbled, rest split up into 3 or 4 pieces.
3	0.71% KPO_3	Specimen crumbled and broke up.
4	0.23% NaCl	Specimen partly crumbled rest retained its original form.
5	1.42% KPO_3	About same as Test No. 4.
6	0.46% NaCl	Do.
7	0.92% NaCl	Do.
8	4.26% KPO_3 1.38% NaCl	Little crumbled on bottom rest split up into large pieces retaining some of its original form.

In the above tests, Example 3, the ratio of KPO_3 :NaCl is slightly greater than 3:1.

Example No. 4

[Treating agents used are $NaPO_3$ (insoluble sodium monometaphosphate) and K_2CO_3 (potassium carbonate)]

Test No.	Type of aqueous suspension	Appearance of shale after 24 hours
1	Control: Distilled water	Specimen broke into 15-20 pieces.
2	Control: 2 volume sodium silicate 1 volume saturated NaCl solution	Specimen broke into 3 pieces.
3	Control: 30% K_2CO_3	Specimen broke into 3 large, 2 small pieces, some crumbled off sample.
4	0.75% $NaPO_3$	Specimen broke into about 8 pieces.
5	1.5% K_2CO_3	Specimen broke into about 4 pieces, considerable spalled off bottom.
6	1.5% $NaPO_3$	Specimen broke into 3 pieces, small amount spalled off.
7	3.0% $NaPO_3$	Specimen broke into 3 pieces, a little crumbled off.
8	6.0% K_2CO_3	Specimen broke into 4 or 5 pieces, some crumbled off.
9	30.0% K_2CO_3	Specimen broke into 3 pieces, some crumbled off.

In the above tests, Example 4, the ratio of $NaPO_3$: K_2CO_3 is 1:2.

Example No. 5

[Treating agents used are KPO_3 (insoluble potassium monometaphosphate) and sodium silicate]

Test No.	Type of aqueous suspension	Appearance of shale after 24 hours
1	Control: Distilled water	Specimen broke in 1 large and about 10 small pieces.
1a	Do.	Specimen broke in about 10 pieces.
2	Control: 2 volumes sodium silicate 1 volume saturated $NaCl$ solution	Specimen broke in several large and about 6 or 7 smaller pieces.
2a	Control: 2 volumes sodium silicate 1 volume saturated $NaCl$ solution	Specimen broke in 5 pieces.
3	Control: 2.5% sodium silicate solution	Specimen broke in about 6 pieces.
3a	Do.	Specimen broke in 2 large and about 6 or 7 smaller pieces; some crumbled off the bottom.
4	0.75% KPO_3	Specimen cracked off the top. 2 pieces.
4a	0.125% sodium silicate	Specimen in 1 piece; a little crumbled off specimen.
5	0.75% KPO_3	Specimen in 1 piece.
5a	0.25% sodium silicate	Specimen broke in 2 large and about 7 smaller pieces; some crumbled off bottom.
6	3.0% KPO_3	Specimen broke in 3 pieces; some crumbled off the top and side.
6a	0.5% sodium silicate	Specimen cracked in 1 place; retained its complete shape.
7	6.0% KPO_3	Specimen split in 3 pieces; a few chips spalled off the bottom.
7a	1.0% sodium silicate	One piece broke off specimen; some spalled off one side; rest of specimen in excellent shape.
8	9.0% KPO_3	Specimen in one piece.
8a	1.5% sodium silicate	Specimen cracked in 2 pieces.
9	12.0% KPO_3	Specimen broke in 2 pieces; some spalled off one side.
9a	2.0% sodium silicate	Specimen split in 3 pieces.
10	15.0% KPO_3	Specimen broke in 1 large, 2 small pieces.
10a	2.5% sodium silicate	Specimen in 1 piece.

In the above tests, Example 5, the ratio of KPO_3 to sodium silicate is 6:1.

Example No. 6

[Treating agent used was sodium phosphate glass]

Test No.	Type of aqueous suspension	Appearance of shale after 15 minutes
1	Control: Distilled water	Specimen crumbled and broke up.
2	2.5% sodium phosphate glass	Same as Test No. 1, except specimen crumbled into finer pieces.
3	5.0% sodium phosphate glass	Same as Test No. 2, except specimen crumbled into still finer pieces.
4	10% sodium phosphate glass	Same as Test No. 3, except specimen crumbled into pieces finer than in Test No. 3.
5	15% sodium phosphate glass	Same as Test No. 4, except finer pieces.
6	20% sodium phosphate glass	Same as Test No. 5 except finer pieces.
7	25% sodium phosphate glass	Same as Test No. 6 except specimen crumbled into pieces finer than in Test No. 6.

NOTE: The phosphate glass used in the above tests was a sodium phosphate glass having a ratio of $Na_2O:P_2O_5$ of about 1.1:1. It will be observed that the sodium phosphate glass was less effective than the distilled water control, Test No. 1.

Example No. 7

[Treating agent used was sodium silicate ($Na_2O:SiO_2$ ratio 1:2.00)]

Test No.	Type of aqueous suspension	Appearance of shale after 24 hours
1	Control: Distilled water	Specimen broke into 3 large pieces, 1 small piece; small amount spalled off.
2	4.86% sodium silicate	Specimen broke into 3 pieces; some spalled off.
3	9.72% sodium silicate	Specimen broke into 4 pieces; some spalled off.
4	14.58% sodium silicate	Specimen broke into 2 pieces; some spalled off.
5	19.44% sodium silicate	Specimen broke into 2 pieces; some spalled off.
6	24.3% sodium silicate	Specimen in one piece; some spalled off.

NOTE: This example is prior art.

The tests set forth in the foregoing examples show clearly the efficacy of the water-insoluble alkali metal metaphosphates whether employed as mixtures of $NaPO_3$ and KPO_3 as in Example 1; whether employed singly but in admixture with a water-soluble sodium salt, as mixtures of KPO_3 and sodium phosphate glass, as in Example 2; or as mixtures of KPO_3 and sodium chloride, as in Example 3; or as a mixture of water-insoluble $NaPO_3$ and an alkaline water-soluble potassium salt, such as K_2CO_3 , as in Example 4; a mixture of KPO_3 (water-insoluble) and an alkaline sodium salt such as sodium silicate, as in Example 5.

It will be noticed by the comparison of Examples 5 and 7, that the mixture of KPO_3 and silicate is effective even though the concentration of

silicate is far below the effective concentration of the silicate used either alone or with sodium chloride. See Examples 2, 3, and 4.

In the examples given, the column "Appearance of shale" after the stated times, merely indicates the length of time during which frequent observations were made of the condition of the lumps of shale (oven-dried kaolin). After these time periods, the lumps were observed only occasionally. For instance, in the test represented by Example 1, the test specimens were preserved for a period of about two months, at the end of which time the test specimens in KPO_3-NaPO_3 suspension were in the condition indicated after 48 hours. This was true of the specimens in Example 3 after a period of about

two months. With respect to Example 1, the test specimens were removed from the KPO_3 - NaPO_3 suspensions, washed in water. Some of them were immersed in water for several days and one specimen was immersed in water for about two weeks. These specimens did not disintegrate when given such drastic treatment.

A test corresponding to Examples 1 and 2 was made wherein the samples were heated in an oven to 110°C . for a period of four days while in a mixed suspension of KPO_3 and NaPO_3 , and KPO_3 and sodium phosphate glass, respectively, and disintegration did not occur. The test specimens after removal from the suspension were washed in water and found to be stronger and harder to break than the original test specimens. These prolonged tests corresponding to Examples 1 and 2 indicate that the specimens in other examples herein stated and illustrating the invention, would behave similarly when subjected to similar drastic conditions.

Observation of the tests set forth in Examples 1 and 2 over periods of time longer than those noted in the time column, indicates that even though some of the test specimens cracked, hydrous disintegration of the specimens was prevented and inhibited.

Where an alkali metal water-insoluble monometaphosphate and an alkali-metal compound for solubilizing the insoluble monometaphosphate are used to treat the mud, the ratio of the alkali-metal monometaphosphate to the alkali-metal compound may vary from about 1:2 to 10:1.

When water-insoluble potassium metaphosphate and sodium silicate are employed, the ratio of the potassium metaphosphate to the sodium silicate may vary from about 3:1 to about 10:1.

It is obvious that modifications and variations of the invention as hereinbefore described may be made without departing from the spirit and scope thereof.

What I claim as new and desire to secure by Letters Patent is:

1. A drilling mud having the property of inhibiting the disintegration of hydrolyzable shale comprising finely divided solids commonly used in drilling muds, water, and a mixture of water-insoluble potassium monometaphosphate and water-insoluble sodium metaphosphate, the dry weight of said mixture in the mud being from about 1% to about 30% of the weight of the water content of the mud and the ratio of potassium monometaphosphate to the sodium monometaphosphate being about 1:1.

2. A drilling mud having the property of inhibiting the disintegration of hydrolyzable shale comprising finely divided drilling mud solids, water, and a mixture of water-insoluble potassium monometaphosphate and a water-soluble alkali metal the alkali-metal of which is other than potassium the amount of said mixture in the mud on a dry weight basis being from about 1% to about 30% of the weight of the water in the mud and the ratio of water-insoluble potassium monometaphosphate to the water-soluble compound being in the range of from about 2:1 to 10:1.

3. A drilling mud having the property of inhibiting the disintegration of hydrolyzable shale comprising finely divided drilling mud solids, water, and a mixture of water-insoluble potassium monometaphosphate and a water-soluble sodium phosphate, the dry weight of said mixture being from about 1% to about 30% of the weight of the water used in the mud and the ratio

of water-insoluble potassium monometaphosphate to water-soluble sodium phosphate being about 2:1.

4. A drilling mud having the property of preventing and inhibiting the disintegration of hydrolyzable shale comprising finely divided solids, water, and a mixture of water-insoluble potassium monometaphosphate and a water-soluble sodium compound the dry weight of said mixture being from about 1% to about 30% of the weight of the water used in the mud and the ratio of water-insoluble potassium monometaphosphate to water-soluble sodium compound being in the range of from 2:1 to 10:1.

5. In the drilling of wells with the use of a drilling mud, the method of preventing the disintegration of hydrolyzable shale which comprises circulating through the well, as the drilling proceeds through formations of shale which disintegrate on contact with water, a drilling mud comprising finely divided solids and water, and adding to said mud a mixture of water-insoluble potassium monometaphosphate and water-insoluble sodium metaphosphate, the dry weight of said mixture being from about 4% to about 20% of the weight of the water content of the mud and the ratio of the potassium monometaphosphate to the sodium metaphosphate being about 1:1, said mixture being added in amount sufficient to inhibit the disintegration of said shale by the water in said mud and being substantially in excess of that amount required for reducing the viscosity of such drilling mud.

6. In the drilling of wells with the use of a drilling mud the method of preventing the disintegration of hydrolyzable shale which comprises circulating through the well, as the drilling proceeds through hydrolyzable shale formations, a drilling mud comprising finely divided solids commonly used in drilling muds and water, and adding to said mud a mixture of water-insoluble potassium monometaphosphate and a sufficient amount of a water-soluble alkali-metal compound the alkali-metal of which is other than potassium, to exert a solubilizing effect upon the water-insoluble potassium monometaphosphate, said mixture being added in amounts based on the weight of water in the mud sufficient to inhibit the disintegration of said shale formation by the water in said mud and being substantially in excess of that amount required for reducing the viscosity of such a drilling mud.

7. In the drilling of wells with the use of a drilling mud the method of preventing the disintegration of hydrolyzable shale which comprises circulating through the well, as the drilling proceeds through hydrolyzable shale formations, a drilling mud comprising finely divided solids and water, and adding to said mud a mixture of water-insoluble potassium monometaphosphate and a sufficient amount of a water-soluble sodium phosphate to exert a solubilizing effect upon the water-insoluble potassium monometaphosphate, in amounts based on the weight of water in the mud sufficient to protect such shale against disintegration by the water in said mud and in amount substantially in excess of that required to reduce the viscosity of such drilling mud.

8. In the drilling of wells with the use of a drilling mud the method of preventing the disintegration of hydrolyzable shale which comprises circulating through the well, as the drilling proceeds through hydrolyzable shale formations, a drilling mud comprising finely divided solids com-

monly used in drilling muds, water, and adding to the mud a mixture of water-insoluble potassium monometaphosphate and a water-soluble sodium compound the amount of said water-soluble sodium compound being sufficient to exert a solubilizing effect on the water-insoluble potassium monometaphosphate and said mixture being added on the basis of weight of water in the mud and in amounts sufficient to prevent the water in said mud from hydrolyzing said shale and thereby checking disintegration thereof said added amounts being substantially in excess of those required to reduce the viscosity of such drilling mud.

9. The method of preventing an aqueous drilling mud from attacking and causing disintegration of hydrolyzable shales encountered in formations through which a well is drilled, comprising adding to the mud a treating agent containing a water-insoluble alkali metal monometaphosphate, the amount of monometaphosphate added to the mud being, on a dry weight basis, from about 1% to about 30% of the weight of water in the mud.

10. A method according to claim 9 in which the treating agent comprises a suspension in water of water-insoluble sodium and potassium metaphosphates wherein the relative amounts of water-insoluble sodium metaphosphate to water-insoluble potassium metaphosphate are such as to effect a solubilizing reaction between said metaphosphates, the amount of phosphates of such agent added to the mud being, on a dry weight basis, from about 1% to 10% based on the weight of water in the mud.

11. A method according to claim 9 in which the treating agent comprises a suspension in water of water-insoluble sodium and potassium metaphosphate the relative amounts of water-insoluble sodium metaphosphate and water-insoluble potassium metaphosphate being such that a mutual solubilizing reaction is effected and the amount of phosphates of such agent added to the mud being, on a dry weight basis, from about 4% to 20% based on the weight of water in the mud.

12. The method of preventing an aqueous drilling mud from attacking and causing disintegration of hydrolyzable shales encountered in formations through which a well is drilled, which

comprises adding to the mud a treating agent containing a water-insoluble alkali metal monometaphosphate and an alkali-metal compound the alkali metal of which is dissimilar to the alkali metal of said monometaphosphate which compound acts as a solubilizing agent for the monometaphosphate when contacted with said water-insoluble alkali-metal monometaphosphate in the presence of water, the amount of monometaphosphate added to the mud being, on a dry weight basis, from about 1% to about 30% of the weight of water in the mud and the ratio of the monometaphosphate to the solubilizing agent being in the range of from about 10:1 to about 1:2.

13. A drilling mud for inhibiting the disintegration of hydrolyzable shale comprising finely divided solids, water, and a mixture of water-insoluble potassium monometaphosphate and a water-soluble sodium compound, said water-soluble sodium compound being in sufficient concentration to exert a solubilizing effect on the water-insoluble potassium monometaphosphate, the amount of said mixture being substantially in excess of that required for reducing the viscosity of such drilling mud and being at least that amount required to retard the disintegration of hydrolyzable shale, which amount may be determined by tests.

NORMAN E. MARTELLO

It is hereby certified that error appears in the printed specification of the above numbered patent requiring correction as follows: Column 9, line 60, claim 2, after the word "metal" and before "the" insert *compound*; and that the said Letters Patent should be read with this correction therein that the same may conform to the record of the case in the Patent Office.

Signed and sealed this 7th day of September, A. D. 1948.

[~~SEAL~~]

THOMAS F. MURPHY,
Assistant Commissioner of Patents.
